UNITED STATES PATENT OFFICE.

REUBEN H. HOLDER, OF WINSTON-SALEM, NORTH CAROLINA.

CLOTH-SAVING DEVICE.

1,383,116.

Specification of Letters Patent. Patented June 28, 1921.

Application filed October 7, 1919. Serial No. 329,130.

To all whom it may concern:

Be it known that I, REUBEN H. HOLDER, a citizen of the United States, residing at Winston-Salem, in the county of Forsyth and State of North Carolina, have invented new and useful Improvements in Cloth-Saving Devices, of which the following is a specification.

This invention relates to an improved 10 method of cutting out garments and to the pattern for securing the lines on which the goods from which the garment is made and are cut.

The principal purpose of the invention is 15 to eliminate practically all waste of the goods by so cutting the goods that the waste pieces may be utilized for flaps and gussets in the garment.

Another object of the invention is to provide 20 means whereby the different lines on which the goods are to be cut may be easily and quickly marked on the goods from a pattern.

The invention also consists in certain other 25 features of construction and in the combination and arrangement of the several parts, to be hereinafter fully described, illustrated in the accompanying drawings and specifically pointed out in the appended claims.

30 In describing my invention in detail, reference will be had to the accompanying drawings wherein like characters denote like or corresponding parts throughout the several views, and in which:—

35 Figure 1 is a rear view of a garment for which the invention is intended.

Fig. 2 is a face view of my improved pattern.

Fig. 3 is a rear view.

40 Fig. 4 is a detail section on line 4—4 of Fig. 2.

Fig. 5 is a view showing the pattern placed on a pile of stock.

45 Fig. 6 is a fragmentary view showing a modification.

As shown in Fig. 1 the garment for which the invention is designed is the well known union suit which is made of tubular stock as is well known in the art. In cutting out these 50 garments from the stock it has been customary to use three separate pattern pieces at the upper end to form the arm holes and the front and rear part of the neck and another part to form the reduced portions for the legs. Furthermore the correct placing of the part for indicating the line of the arm

holes must be found by a rule. In this way a great amount of time is lost in placing the different parts of the pattern in position and the leg pattern necessitated the cutting away 60 of a large piece at each side edge of the stock at its lower part and these pieces were regarded as waste.

In carrying out my invention I aim to provide a pattern from a single piece of material 65 so formed that all the lines on which the goods is to be cut may be marked and correctly positioned therefrom and with but little waste of material.

My invention comprises a pattern board 1, 70 which may be made of any suitable material and at its upper end has one corner cut-away to leave a crescent-shaped wall 2. The opposite upper corner is cut-away to provide a recess 5 which has its bottom wall slightly 75 inclined. The board is also provided with a slot 6 intermediate its side edges, said slot being cut through the upper end of the board and extending to an opening 7. Strips of metal 8 may be secured to the board for connecting the parts on each side of the slot 80 together. The lower part of the board has one edge cut-away to leave a long inclined edge 9 which extends from the lower end of the board to a point at the straight edge of 85 the board an appreciable distance from the center. The other side edge of the board is slightly inclined inwardly as at 10, this incline beginning at a point approximately opposite the starting point of the inclined 90 edge 9.

The transverse strips 11 of metal or the like are secured to the rear face of the board and other strips 12 are slidably secured to the front face by means of the screws 13 passing through slots 14 formed in said strips 12 and engaging screw threaded holes in the strips 11. Each of the strips 12 is bent at right angles so that said strips 12 will act as 95 adjustable gages for positioning the pattern 100 board on the bundle of stock as shown in Fig. 5.

As shown in said Fig. 5 the pattern board is placed on the pile of stock with the gages 105 engaging one edge of the pile of stock. Lines are then marked on the upper piece of stock by chalk or the like by running the chalk along the edges of the recesses 4 and 5, along the slot 6 and also along the inclined edges 9 and 10. The chalk is also run along 110 the top wall of the opening 7 so as to indicate the limit of the cut made on line 6.

The pile of stock is then placed under the cutting tool and the stock cut on said lines. Thus the stock will be formed with the neck portions and the arm holes in the trunk portion and below the trunk portion the stock portion is reduced and its edges cut to form the leg portions.

The portion of the stock cut on the line 9 I use for the flap portion of the garment, 10 said flap being shown at A in Fig. 1.

In the smaller sizes of garments the cut made on line 10 is made close to the edge of the stock so as to simply open the stock at this point and the strip of waste is very 15 small. However, in the large size garments this strip is of considerable size and I use this strip as a gusset for connecting the leg portion to the flap, as shown at B in Fig. 1.

I secure small metal clips 15 to the face 20 of the pattern board with their pointed ends at the edges of said board so as to indicate where the stock is to be marked to indicate where the flap is to be sewn to the garment.

As the larger sized garments are usually 25 provided with a cuff at the ends of the legs, such ends are reduced in width to receive said cuffs and in order to indicate this reduction I form curved slots 16 in the leg portion of the pattern board so that the 30 chalk may be passed through said slots to mark the curved lines on the stock for indicating where the stock is to be cut.

If desired the leg part of the pattern board may have its corners rounded instead 35 of forming the slots therein. This construction is shown in Fig. 6 where the rounded corners are indicated at 16'.

What I claim is:—

1. A pattern board of the class described 40 having one corner provided with a recess having a curved wall and the adjacent corner having a recess therein having its bottom slightly inclined, said board also having a longitudinally extending slot beginning at its upper edge and extending to a point below the recess, said slot being located midway the side edges of the board.

2. A pattern board of the class described comprising a trunk part and a leg part, one

of the upper corners of the trunk part having a recess formed therein provided with a curved wall and the other upper corner having a recess therein having its bottom slightly inclined, said trunk part also having a longitudinally extending slot beginning at its upper edge and extending to a point below the above mentioned recesses and the leg part of the board having the edge thereof immediately below the curved wall recess inclined inwardly to a great extent and the other edge of the leg part being inclined a slight extent.

3. A pattern board of the class described comprising a trunk portion and a leg portion, said leg portion having its edges tapering inwardly toward its end, one of said edges having a greater taper than the other edge, the upper end of the trunk having a curved recess in one corner and a small substantially rectangular recess in the other corner and a centrally located slot extending longitudinally from the upper edge to a point below the recess, said board having an opening at the inner end of said slot.

4. A pattern of the class described comprising a trunk portion and a leg portion, said leg portion having its edges tapering inwardly toward its end, the upper part of the trunk portion having its corners cut-away and provided with a centrally located 70 longitudinally extending slot, a strip connecting the parts of the board on each side of the slot together and adjustable gage strips carried by said board.

5. A pattern of the class described comprising a trunk portion and a leg portion, said leg portion having its edges tapering inwardly toward its end, the upper part of the trunk portion having its corners cut-away and provided with a centrally located 80 longitudinally extending slot, a strip connecting the parts of the board on each side of the slot together and adjustable gage strips carried by said board and pointers carried by the board.

In testimony whereof I affix my signature.

REUBEN H. HOLDER.
